WEB GUIDING AND TENSIONING DEVICE

Charles H. Trimble and Fred J. Wagner, Winston-Salem, N. C., assignors to Western Electric Company, Incorporated, New York, N. Y., a corporation of New York

Application December 16, 1953, Serial No. 398,494

3 Claims. (Cl. 271—2.6)

This invention in general relates to means for guiding and applying constant tension to a moving web, and more particularly to novel means for guiding a moving web to obtain angular displacement and for maintaining the moving web in substantially constant tension with respect to the guiding means.

At the termination in the line of a moving web it is customarily the practice to employ a reel or the like on which the web is wound. During such winding operations some of the essential elements are to maintain the moving web in proper relation to the reel so that there will be no buckling, creasing, or wrinkling in the web, and also to maintain the edge of each successive turn of the web upon the reel directly above the preceding edge. That is, the moving web must be so guided upon the reel as to prevent overrunning of the edges of successive layers.

The web guiding devices that have been developed in the past have proven unsatisfactory for guiding webs moving in substantially a straight line in that they fail to compensate for such factors as slackening of the web due to normal variations in machinery speeds, elasticity of the web, or other conditions. Previous web guiding devices that employ rollers, to be effective, usually require that the web be in contact with the guide rolls for a considerable portion of the roll circumference. Therefore, for a web moving in substantially a straight line the heretofore guide devices have proven to be unsatisfactory.

It is an object of this invention to overcome the limitations described above.

It is a further object of this invention to provide a web guiding means that may also be employed effectively in the line of a web moving in substantially a straight line.

A still further object of the present invention is to provide a means for maintaining a moving web in constant tension with respect to the guiding means.

Another object of the present invention is to provide means for accurately controlling the web guiding means.

Yet another object of the invention is the provision of adjustable means to control the guiding of the web.

The invention further resides in certain novel features of parts, and further objects and advantages thereof will become apparent to those skilled in the art to which it pertains from the following description of the present preferred embodiment thereof described with respect to the accompanying drawings in which similar reference characters represent corresponding parts in the several views, in which:

Fig. 1 is an isometric view of an embodiment of the invention;

Fig. 2 is a front view with the control linkage and connections illustrated in section;

Fig. 3 is an end view of the invention;

Fig. 4 is a plan view of the invention;

Fig. 5 is an exaggerated diagrammatic view showing the tilt of the upper roller to guide the web to the left; and

Fig. 6 is an exaggerated diagrammatic view showing

2

the tilt of the upper roller to guide the web to the right.

Generally, the present invention involves a device for guiding and tensioning a moving web. The device consists of a lower roller to maintain substantially constant upward tension against a moving web, an upper roller pivotably movable in a vertical plane to impart a slight twist to the moving web to effect a correction in the lateral movement of the web, and a calibrated linkage to set the degree of pivotal movement of the upper roller.

10 In Fig. 1 of the drawings, the reference numeral 10 represents generally the web guiding and tensioning means which is the principal object of this invention. Although the web guiding means is here shown secured to a specific stand or structure, this stand may take various modifications in the present invention as it will become obvious that the hereinafter described devise may be installed directly in the line of any moving web or to other forms of support.

Referring now particularly to Fig. 1, an L-shaped 20 member 11 is secured by any suitable means to a vertical member 12 to form a downwardly extending bifurcated portion. Journaled within this bifurcated portion by means of suitable bearings 13 is an upper roller 14. For the purposes of the following description the term "roller" 25 will be used but it being understood that this invention is not limited to the use of a roller where it is obvious that a sliding shoe or curved member in frictional contact with a moving web may be substituted for the roller. The bearings 13 are more clearly shown in Fig. 2 where 30 the one on the left is shown in section. The downwardly extending bifurcated portion formed by the members 11 and 12 is pivotable about an axis defined by the center line of a bolt 16 to form a tiltable support for the upper roller 14. The opposite end 18 of the bolt 16, more 35 clearly shown in Fig. 3, is secured to a suitable structure indicated here as a base structure 17. It will be observed that if there were no other connections or obstructions, the united members 11 and 12 would be able to rotate freely about the axis of the bolt 16. However, attached to the upper portion of the member 12 is a linkage as shown in the drawings and which will now be described.

Referring to Fig. 2, this linkage is indicated in cross section to more clearly show its operation to control the degree of tilt of the joined members 11 and 12. A link

45 20 is firmly secured by suitable means to the base structure 17. An extended portion 21 of the link 20, not shown in Fig. 2 because of the sectional view, but clearly shown in Figs. 1 and 4, is provided for the purpose of supporting the outer end of a shaft 22. The other end of 50 shaft 22 is secured to the support 17. One end of a link 23 is pivotally mounted on the shaft 22. The opposite end of the link 23 is bifurcated as clearly shown in the drawings, and nested within this bifurcation is a link 25 which is mounted pivotally about a shaft 24 extending 55 through the bifurcation. The link 25 is threaded to receive a threaded shaft 27, Figs. 2 and 4. The shaft 27 extends from the link 25, through the upper portion of the member 12 and is secured as an integral part of a hub 28. A shoulder 29 fixedly secured to the shaft 27, and 60 the hub 28 also fixedly secured to the same shaft prevent any lateral movement of the shaft 27 with respect to the upper portion of the member 12. However, the shaft 27 is rotatable by means of a handle 30. An integral portion of the hub 28 is a scale 31 which is suitably designed

65 to indicate relative rotational displacement of the shaft 27. The operation of this linkage in controlling the degree of rotational displacement of the upper roller 14 will now be described.

Referring particularly to Fig. 2, the axis of rotation of the upper roller 14 is shown substantially horizontal. Should it be required to guide a moving web to the left, that is, to the left looking at Fig. 2, the axis of rotation of

the roller 14 must be rotated slightly counterclockwise about the bolt 16. This is accomplished by turning the handle 30 counterclockwise. This movement of the handle 30 threads the shaft 27 out of the link 25 urging the upper extension of the member 12 outwardly, thereby resulting in the desired counterclockwise rotational displacement of the joined members 11 and 12 about the axis of the bolt 16. As the roller 14 is journaled within the downwardly extending bifurcation of the joined members 11 and 12, any rotational displacement given to these members governs also the rotational displacement of the roller 14. Likewise, should it be required to guide a moving web to the right, the handle 30 may be turned clockwise thereby threading the shaft 27 into the link 25 resulting in a clockwise rotational displacement of the joined members 11 and 12 about the axis of the bolt 16. It may now be evident that the principal function of the links 20, 23, and 25 is to furnish a support, free from binding, against which the shaft 27 may be operated to result in a predetermined rotational displacement for the guide roller 14.

Although the required tilt of the guide roller 14 is very slight to give the result desired, to more fully understand the actual operation of the links to control this tilt, assume that a large tilt, or rotational displacement, is desired. This is shown diagrammatically in Figs. 5 and 6. To obtain a large tilt to the left as illustrated in Fig. 5, the handle 30 must be given several turns, counterclockwise. This will thread the shaft 27 further out of the link 25 urging the upper portion of the member 12 to rotate counterclockwise about the axis of the bolt 16. But to prevent binding, the link 25 will turn slightly counterclockwise about its shaft 24. At the same time the shaft 24 will be raised by a clockwise movement of link 23 about its pivot shaft 22. The link 20 acts as an anchor link and as an additional support for the shaft 22.

To obtain a large tilt to the right, as illustrated in Fig. 6, the handle 30 is given several turns clockwise. This will thread the shaft 27 further into the link 25 thereby drawing the upper portion of the member 12 toward the link 25 in a clockwise rotational movement about the axis of the bolt 16. The links again will adjust themselves to prevent any binding of the shaft 27. The link 25 will be rotated slightly clockwise about its shaft 24 and at the same time the shaft 24 will be moved downward in a rotational movement about the axis of the shaft 22. This is accomplished by the counterclockwise movement of the link 23.

To effect maximum efficiency from the guide roller, a lower roller 40 is positioned to urge the moving web against the guide roller 14 as shown in the exaggerated views in Figs. 5 and 6.

In order to clearly disclose the operation of the tensioning means, refer more particularly to Figs. 2 and 3. The lower roller 40 is located on a vertically movable platen 41 by means of suitable bearings 42. The platen 41 is capable of movement only in a vertical direction. By maintaining substantially constant upward pressure on the platen 41, the lower roller 40 will maintain a moving web in substantially constant pressure against the guide roller 14. This is particularly important for a web moving in a straight line where there would be theoretically only point contact with the guide roller.

The platen 41 is movable vertically on two columns 43-43 which are fixedly mounted in an upright position as shown in Figs. 2 and 3. The upper ends of the columns 43-43 terminate in caps 44-44 to form shoulders against which compression springs 45-45 may act. Fixedly secured to the underside of the platen 41 are hubs 46-46 to insure against any possible angular movement of the platen. The platen 41 is urged vertically upwardly by means of any standard hydraulic cylinder 47. The

interaction between the upward force of the hydraulic cylinder 47 and the downward force of springs 45-45 when no web is passing between the rollers is such that the platen 41, including the lower roller 40, is hydraulically floatingly secured. Such floating suspension of the roller 40 assures tensioning of the web even though the web may vary in thickness during manufacture.

It will be understood that the embodiment herein described is merely illustrative of the invention and one application thereof and that modifications can be made and it is capable of other applications.

What is claimed is:

1. A web guiding device comprising a first roller, a second roller, means to tilt said first roller with respect to the surface of a web, a vertically movable platen to support said second roller, a plurality of columns extending vertically through said platen, caps mounted on the upper end of said columns, compression springs surrounding said columns and positioned between said caps and said platen and tending to urge said platen downwardly, and hydraulic means acting upwardly against said platen with constant pressure to overcome the action of said compression springs.

2. A web guiding device comprising a support tiltable with respect to the surface of a web and having a downwardly depending bifurcated portion, an upper roller, said upper roller being journaled within said downwardly depending bifurcated portion of said tiltable support, a base structure, a flexible linkage anchored at one end to said base structure and secured to said tiltable support at the other end, a threaded member in said flexible linkage, a handle secured to said threaded member to change the effective length of said flexible linkage, a vertically movable platen, a lower roller mounted on said platen, and means to floatingly support said platen between an upwardly acting hydraulic means and downwardly acting compression springs.

3. A web guiding device comprising a base structure, a support tiltable with respect to the surface of a web, an upper roller mounted on said support, a lower roller, a flexible linkage to tilt said upper roller with respect to said lower roller, said flexible linkage comprising a first link secured to the base structure, a first shaft secured at one end to the base structure and at the opposite end to said first link, a second link mounted pivotally about said first shaft at one end and bifurcated at the opposite end, a second shaft secured in the bifurcated end of said second link, a third link mounted rotatably at one end about said second shaft and having a threaded aperture in the opposite end thereof, a rod threaded at one end within the aperture of said third link and attached to said tiltable support at the opposite end, and a handle secured to said threaded rod for varying the effective length of said linkage.
